FIG. 5

UNITED STATES PATENT OFFICE

2,564,842

DEVICE FOR MOISTENING ENVELOPE FLAPS

Floyd E. Helmuth, Mission, Kans.

Application April 7, 1947, Serial No. 739,836

1 Claim. (Cl. 91—54.4)

1

This invention relates to new and useful improvements in a device for moistening envelope flaps and has particular reference to a simple device whereby this operation may be conveniently and expeditiously carried out.

The principal object of the present invention is the provision of an envelope flap moistener wherein the flap of an envelope is passed between a moistening pad and a resilient pressure arm, said arm urging the flap against said pad.

Another object is the provision of means for preventing the drying of the surface of the moistening pad during extended periods of non-use.

Other objects are simplicity and economy of construction, and ease and convenience of use.

With these objects in view, as well as other objects which will appear during the course of the specification, reference will now be had to the drawing, wherein:

Figure 1 is a plan view of an envelope flap moistener embodying my invention, and showing an envelope flap positioned in moistening relation therein.

Fig. 2 is a front elevation of the device.

Fig. 3 is an enlarged vertical section taken on line III—III of Figure 2.

Fig. 4 is a plan view of an envelope flap moistener employing a resilient pressure arm of modified form.

Fig. 5 is an enlarged fragmentary front elevation of the flap moistener shown in Figure 4, with the pressure arm partially broken away and showing the flap of an envelope in operative relationship thereto.

Like reference characters apply to similar parts throughout the several views, and the numeral 10 applies to a circular bottle for containing water and having a screw cover 12, said cover having a central aperture 14 extending therethrough. A gasket 16 adapted to bear against the upper edge of bottle 10 and the lower surface of cover 12 provides a watertight seal between said bottle and said cover.

Cover 12 carries a moistening pad 18 comprising a fabric covering 20 filled with cotton waste 22 or other soft, absorbent material. The edges of covering 20 are clamped between the lower surface of gasket 16 and a circular plate 24, said plate forming a supporting base for pad 18 and retaining the cotton waste therein. A plurality of bolts 26 spaced about aperture 14 and passing respectively through cover 12, gasket 16, pad covering 20, and plate 24, serve to clamp the entire moistening pad structure into a unit. The pad extends upwardly through aperture 14 and

above cover 12. A length of wicking 28, the depending ends of which are immersed in the water carried in bottle 10, extends upwardly into pad 18 through a slot 30 in plate 24, and is rebent therein to provide even distribution of moisture through the pad.

A pressure arm 32 comprising a flat strip of spring material is rigidly fixed at one end to the upper surface of cover 12 by means of one of bolts 26, and is adapted to extend over and to bear resiliently against the top of moistening pad 18. Since the pressure arm is substantially flat, and since the moistening pad has a substantially flat top, there is a considerable area of contact between the pressure arm and pad. The longitudinal edges of the pressure arm are curved upwardly to facilitate the insertions of an envelope flap between the arm and the pad.

The operation of the envelope flap moistener 20 is substantially as follows. With the parts assembled as shown in Figure 3, water travels upwardly through wicking 28 and into moistening pad 18, wetting said pad evenly and thoroughly. The flap 34 of an envelope 36 is inserted, gummed 25 side down, between pressure arm 32 and moistening pad 18, and is manually advanced therebetween to pass all parts of the adhesive of the flap in contact with said moistening pad, thus wetting said adhesive evenly. The flap may then be withdrawn and the envelope sealed in the usual manner. The force exerted by pressure arm 32 is light, and therefore permits very easy insertion of the envelope flap. Stability is given to the entire device by the weight of the water in the lower portion of bottle 10. Since air is excluded from that portion of the surface of moistening pad 18 which normally is contacted by pressure arm 32, said pad surface will not become dry even after long periods of non-use, and the moistener 30 is thus maintained in readiness for instant use at all times.

In the modified form shown in Figures 4 and 5, the pressure arm 38 comprises a single length of spring wire bent to substantially a U conformation having parallel reaches 40 and 42, the free ends of which are rigidly attached to cover 12. Said pressure arm is adapted to bear resiliently against the top of moistening pad 18 with opposite reaches 40 and 42 disposed on either side of the center of said pad so that the arcuate surface of the pad extends between said opposite reaches as shown in Figure 5. Thus, when an envelope flap 34 is drawn between the pressure arm and the moistening pad, it will be forced 50 upwardly between reaches 40 and 42 by the pad,

thereby insuring an intimate contact between the flap and the moistening pad.

What I claim as new and desire to protect by Letters Patent is:

A device for moistening envelope flaps comprising a container for water, a removable screw cover for said container having a circular aperture formed therein, an annular gasket disposed between said cover and said container, a closure plate for said aperture disposed inside said cover and overlapping the inner peripheral edge portion of said gasket, a piece of fabric covering said aperture and having its edge portions disposed between said closure plate and said gasket means for securing said closure plate to said cover whereby said gasket and said fabric are clamped therebetween, absorbent material packed between said closure plate and said fabric to form a pad protruding outwardly through said aperture, a wick associated with said pad and depending into said container through holes provided in said closure

plate, and a resilient arm secured to the outer surface of said cover and bearing against said pad.
